WITNESS:

UNITED STATES PATENT OFFICE.

ROBERT ZIEGLER, OF CHICAGO, ILLINOIS.

LEVEL AND PLUMB.

Application filed December 27, 1921. Serial No. 525,000.

To all whom it may concern:

Be it known that I, ROBERT ZIEGLER, a citizen of the United States, residing at Chicago, in the county of Cook and State of Illinois, have invented new and useful Improvements in Levels and Plumbs, of which the following is a specification.

This invention relates to a level to be used instead of the well known spirit level, the general object of the invention being to provide a rotary weighted member having indications thereon which will revolve on its axis when the work piece is not level, the indications giving the amount the work piece is out of plumb.

Another object of the invention is to enclose the member in a casing so that the same will be protected from dirt, dust and the like and to provide the casing with several transparent parts so that the rotary member can be seen from different positions.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of the device.

Figure 2 is an elevation thereof.

Figure 3 is a section on line 3—3 of Figure 1.

Figure 4 is a detail view showing the means for adjusting the weight in the rotary member.

Figure 5 is a perspective view of the sleeve 6.

Figure 6 is a view of the ring member 11.

Figure 7 is a view of the ring member which carries the graduations.

In these views 1 indicates the stock which is provided with a recess 2 to receive the rotary member 3. The stock is also provided with counter sunk portions, some of which receive the side plates 4. The reduced upper portion of these side plates are bent inwardly and perforated to receive the reduced screw threaded end of the shaft 5

of the rotary member. A sleeve 6 passes through the member and is secured thereto and this sleeve is rotatably mounted on the shaft. A ball race 7 is secured to each side of the rotary member for receiving the balls 8, said balls being held in the race by the washer 9 which engages the shoulder formed at the junction of the reduced screw threaded end of shaft 5 with its major part. A cover 10, of transparent material, covers each end of the recess 2, said cover being secured to the stock by the ring 11. Each cover is provided with an opening 12 through which the screw threaded end of the shaft 5 passes, rubber washers 13 being located on each side of the cover to protect the same. The parts are held in assembled position by the nuts 14, engaging the screw threaded ends of the shaft 5.

A weight 15 is adjustably secured to the rotary member by means of the bolts 16 and the slots 17 and openings 18 are formed in said member to facilitate the movement of the member by the weight. The sides of the member are provided with arrows 19 which are associated with stationary graduations placed on rings 19', which are held in place by rings 11 and which can be seen through the transparent covers 10 and the circumference of the rotary member is provided with the graduations 20 which may be seen through a window 21 in the upper edge of the stock. Thus the device can be read from either side and from the top.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is —

A tool of the class described comprising a stock having a recess therein and a window in its upper edge communicating with the recess, side plates connected with the stock and arranged at the ends of the recess, each plate having an upwardly extending narrow part, a shaft having its ends carried by said narrow parts, a hollow circular member rotatably supported by said shaft, said member having curved slots in the lower

part of its ends a weight arranged in said member, bolts passing through the slots and engaging the weight for adjustably connecting the weight to the member, transparent members connected with the stock and closing the ends of the recess, indicating marks on the circumference of the circular member and adapted to appear through the

window, indicating marks on the ends of the circular member adapted to appear through the transparent members, ring members held in the ends of the recess and having graduations thereon for cooperating with the marks on the ends of the member.

In testimony whereof I affix my signature.
ROBERT ZIEGLER.
